CLAIM

The ornamental design for a compact disc organizer for visor, as shown and described.

DESCRIPTION

FIG. 1 is a front view showing our design for a compact disc organizer;

FIG. 2 is a top view thereof;

FIG. 3 is a bottom view thereof;

FIG. 4 is a right side view thereof;

FIG. 5 is a left side view thereof;

FIG. 6 is a rear view thereof; and,

FIG. 7 is a perspective view showing the compact disc organizer in use.

The broken line showing of a sun visor is for illustrative purposes only and forms no part of the claimed design.
